UNITED STATES PATENT OFFICE.

FRANK B. WILDMAN AND GEORGE LAWSON BALLARD, OF NORRISTOWN, PENNSYLVANIA, ASSIGNORS TO WILDMAN MFG. CO., A CORPORATION OF PENNSYLVANIA.

THREAD-GUIDE.

1,153,742.

Specification of Letters Patent. Patented Sept. 14, 1915.

Application filed March 7, 1913. Serial No. 752,798.

To all whom it may concern:

Be it known that we, FRANK B. WILDMAN and GEORGE LAWSON BALLARD, a citizen of the United States and a subject of the King of Great Britain, respectively, residing at Norristown, Pennsylvania, have invented certain new and useful Improvements in Thread-Guides, of which the following is a specification.

10 Our invention is designed to provide a simple form of thread guide which will feed the thread with accuracy and certainty and one which is susceptible of adjustment to suit the various conditions in use.

15 The invention consists in the features and combination and arrangement of parts hereinafter described and particularly pointed out in the claims.

In the accompanying drawings Figure 1 is a side view of a thread guide embodying our invention, it being shown in its proper relation to the knitting machine, Fig. 2 is a front view, and Fig. 3 is a plan view of the invention in its relation to the knitting machine. Fig. 4 is a plan view of another form of guard plate, and Fig. 5 is an edge view of said plate, that is of the edge adjacent the needles.

20 In these drawings, 1 is the knitting head and 2 the guide eye for the thread. This eye is disposed with its axis vertical and it preferably consists of a porcelain piece mounted upon a horizontal arm 3. This arm is slotted at 4 and receives a screw 5 by 25 which the arm is held to the post 6 fixed to the horizontal needle guard plate 7. This plate in turn is connected by a slot and screw at 8 to a bracket 9 at the upper end of the post 10 supported on the knitting head.

30 The plate has a long edge adjacent the needles and, as shown in the drawings, the yarn from the guide eye passes down at an inclination and across the inner edge of the guard plate and into contact with the cylinder needles in position to be taken by the needle hooks. Our guide and guard will meet all conditions and character of work.

35 For instance in making tuck stitches in which the latches of the needles remain open to receive the yarn thereon, it is necessary to exert control on the yarn until it is taken by the needle hooks and this is accomplished in our construction because the yarn passes down between the inner edge of the 40 guard and the needles, it finding a guiding

or restraining bearing against said inner edge. By this construction the yarn is guided positively and with certainty to the needles.

45 It will be observed that because of the horizontal disposition of the needle guard plate and the arrangement of the guide eye above it, the yarn after passing the guide eye traverses a free space above the plane of the upper surface of the guard plate, and 50 in case of a knot or lump occurring in the yarn this, after passing through the guide eye 2, will pass along the free space above the horizontal plate and the knot will finally ride upon the upper edge or corner 55 of the inner face or edge of the guard plate instead of working down into the narrow space between this inner edge of the guard plate and the needles where it would be caught, resulting in rupturing the yarn and 60 causing a press off.

65 The post 10 is adjustably mounted in the cam ring of the machine or it may be otherwise supported but in any case we prefer to mount it adjustably so that it may be turned 70 for adjusting the guard plate. In the particular construction shown it is held adjustably by a set screw 11. By loosening this the post may be turned and through the bracket 9 attached thereto, the point of support for the guard plate may be shifted in 75 a direction circumferentially of the needle row and either forward or backward and by loosening at the same time the connection at 80 any desired position of the guard plate 85 may be attained, that is, the plate may be adjusted radially or circumferentially in respect to the needle row or both adjustments may be secured, and further the proper 90 angular position of the guard plate in relation to the needle row may be attained. The adjustment circumferentially of the 95 needle row of course, results from the eccentric relation of the connection 8 in relation to the axis of the post 10.

100 The thread is exposed in its course from the thread eye to the needles. The guide eye is adjustable to various positions by means of its slot and screw attachment and the plate 7 is also adjustable so that the whole 105 device may be adjusted as a whole in relation to the needles, and the guide eye may be adjusted in relation to the edge of the plate 7 and to the guiding projection 110 thereon.

Our invention permits the adjustment of the guide eye and the needle guard, *i.e.*, the plate 7 to be independently performed. That is, the guide eye may be maintained in one position while the guard plate may be adjusted, and conversely the guide eye can be set in different positions without adjusting the needle guard plate. Further, our guide presents, as above referred to, a free space between the guide eye and the point where the needles take the thread, offering no interference to the passage of knots or lumps between the guide eye and the needles, and thus the liability to rupture of the 10 yarn is removed. Furthermore, the form of yarn carrier in general use has the disadvantage of contacting with the hooks of the cylinder needles, which wears and destroys the hooks long before the needle is otherwise 15 worn out. This disadvantage is not present in our construction. The dial needles, in practice being fed by the cylinder needles, lie at a relatively greater distance from the guard than the cylinder needles.

20 The guard plate may be and is preferably formed as shown in Figs. 4 and 5, but for machines of the coarser gages we may construct it as shown in the other figures, wherein at its corner most distant from the 25 guide eye it is provided with a guide 8' for the thread, consisting in the particular construction chosen to illustrate our invention of a projection extending up from the plate 7. Preferably this projection is formed integral with the plate, the corner of the plate 30 simply being turned up as indicated. The position of this projection and the edge of the plate 7 relative to the needles, is such that the thread is controlled up to the point 35 where cylinder needles takes it, this being approximately at the point X. The dial needles work under the plate 7 while the cylinder needles work vertically at the inner edge of the plate, as shown in Fig. 1.

40 We claim:

1. In combination, a needle guard plate horizontally disposed at right angles to the fed needles and adjustably mounted to be set in different positions circumferentially of the needle row and toward and from the same, and a guide eye adjustably mounted on and located above the guard plate, substantially as described.
2. In combination a needle guard plate 45 horizontally disposed and adjustable toward and from the needle row and adjustable as to angular position in respect to the needles and a guide eye located above the surface of the needle guard plate, and supported by 50 said needle guard plate adjustably, said guard plate having a free space between its

inner edge adjacent the needles and the said guide eye for the passage of the thread across said inner edge to the needles.

3. In combination, a needle guard plate, a 55 post supporting the same and rotatably mounted, said post having a connection with the needle guard plate eccentric to its axis to shift the plate along the needle row, said needle guard plate being adjustable in relation to the post toward and from the needles, and a guide eye adjustably mounted on and above the needle guard plate, substantially as described.

4. In combination, a horizontal needle 75 guard plate, a rotatable post having a screw and slot connection with the needle guard plate eccentrically arranged in relation to the axis of the post, and a guide eye supported on the needle guard plate by a screw 80 and slot connection, substantially as described.

5. A thread guide for knitting machines, consisting of a needle guard plate horizontally disposed with a thread guide eye above the same, said needle guard plate having an upwardly extending guiding projection at the corner of the said plate distant from the guide eye, said projection being formed by turning the corner portion of the plate 90 upwardly, substantially as described.

6. A thread guide for a knitting machine, consisting of a horizontal needle guard plate 95 adjustably mounted to be set in proper relation to the needles and having an upwardly extending projection at one corner, an arm having a guide eye, a post extending up from the horizontal needle guard plate and upon which the arm is supported, and an adjustable connection between said arm and post, substantially as described, said guide eye being at the opposite side of the said horizontal needle guard plate from that upon which the projection is located.

7. In combination a needle guard plate 105 disposed horizontally and adjustable toward and from the needle row, and adjustable also into different positions circumferentially in respect thereto, and a yarn guide eye mounted on the needle guard plate and adjustable 110 toward and from the needle row and circumferentially in respect to the same and independently of the adjustment of the needle guard plate, substantially as described.

In testimony whereof, we affix our signatures 115 in presence of two witnesses.

FRANK B. WILDMAN.
GEORGE LAWSON BALLARD.
